ATTORNEY.

Patented Sept. 21, 1926.

UNITED STATES PATENT OFFICE.

FRANK MEGA, OF SOUTH ST. PAUL, MINNESOTA.

EXTENSION TABLE.

Application filed February 19, 1925. Serial No. 10,213.

My invention relates to extension tables and the object is to provide a table having permanently spaced, rigid legs, and a center piece or leaf having hinged members foldable upon the main member and all the members arranged to be lowered to let the end leaves of the table slide together above them.

In the accompanying drawings:—

Fig. 1 is a top or plan view of the improved table with the center leaf in its simplest form.

Fig. 2 is a side elevation of Fig. 1.

Fig. 3 is Fig. 1 turned upside down and the special legs 20 omitted.

Fig. 4 is an enlarged section on the line 4—4 in Fig. 2 with the leaf members 27—28 omitted.

Fig. 5 is a detail edge view of the foldable middle portion of the table.

Fig. 6 is Fig. 5 seen from the right.

Fig. 7 is a bottom view, on a reduced scale, of the center leaf further improved or modified.

Fig. 8 is an end view of Fig. 7 with the leaf members 36 folded upon the top of the main members 30—30^a.

Fig. 9 is Fig. 8 folded also on the line 32 and hinges 31 and thus ready to be swung on the trunnions 33 down into the table frame, the same as the simpler form shown in dotted lines 30—30^a in Fig. 4.

Referring to the drawings by reference numerals, 10—10 designate four legs permanently spaced by cross braces 11 and having their upper ends fixed to the main frame 12 of the table. As internal portions of the main frame there are bars 13 secured by screws 14 and having dovetailed ribs 15 sliding in grooves 16, of slidable bars 17 and 18, which with cross bars 19 form two opposite slidable frame sections each of which may, especially in large tables, have a special supporting leg 20 fixed to a block 21 which is hinged at 22 to make the leg foldable to the horizontal position 20^x in Fig. 2. In said position the leg is yieldingly supported by a resilient arm 23 having a hook 24 engaging the block 21. The downward pressure of the arm upon the block also tends to hold the leg

in its vertical position when in use. For the latter purpose further common locking means (not shown) may also be employed.

Upon each slidable frame section is secured by a cleat 25 and screws 26, or other means, one of the main leaves 27 of the table. When the table is to be only slightly extended beyond a given position I employ loose leaves 28 having dowel pins 29 of any usual type.

With or without the loose leaves 28 I provide a central disappearing leaf composed of two members 30—30^a hinged together by hinges 31 at a central longitudinal line 32 of the table, to fold one upon the other as in Fig. 5 and then be turned on the trunnions 33 to the dotted position 30—30^a in Fig. 4, resting upon a lug 34 of the main frame. Said trunnions are journaled in bearings 33^a fixed on the frame and are formed at the ends of a cleat or supporting bar 35 secured to the leaf member 30.

The arrangement just described is practically the same in the modified form shown in Figs. 7, 8 and 9 only that therein the leaf members 30 and 30^a are given extensions 36 hinged at 37 to fold upon the top of the member 30—30^a, as in Fig. 8, and then with the latter be folded at line 32 to the position shown in Fig. 9, then turned downward at the trunnions and the main table leaves 27 pushed together above the said foldable disappearing section.

In Figs. 4 and 5 38 designates a projecting ledge on the leaf 30 for supporting the edge 39 of the leaf 30^a and prevent sagging of the leaf when there is considerable weight upon the table and the hinges 31 may give some or yield after some wear and tear.

In Fig. 3 40 are studs fixed in the sliding bars 17—18 to prevent their escape from the frame 12.

What I claim is:—

1. In an extension table, a main frame supported on legs, two oppositely arranged frame sections mounted to slide in said frame and having each a fixed leaf, a leaf insert adapted to fill the space between the adjacent edges of the fixed leaves; said insert

composed of two main leaves foldable along a central longitudinal line of the table and having each two extension leaves hinged one to each opposite transverse edge of the main leaf, and a cleat secured to one of the said main leaves and having its ends trunnioned in the main frame of the table, to permit the insert to be turned downward into the frame for closing the fixed leaves above it, and to

be opened level with the tops of the fixed 10 sections when so desired.

2. The structure specified in claim 1, in which the folding along the central line involves hinges along said line and disposed in the extension leaves. 15

In testimony whereof I affix my signature.

FRANK MEGA.
